PUNCHING DEVICE

George F. Wales, Kenmore, N. Y.

Application May 4, 1942, Serial No. 441,594

24 Claims. (Cl. 164—94)

This invention relates to improvements in apparatus for punching or perforating sheet metal and other material and more particularly to punching devices which are intended for use in connection with a press or other power operated machine.

Heretofore punching devices for use in a press and including a holder on which the punch and die units are supported have been made with a stationary die mounted in the base of the holder and a movable punch adapted to be actuated by the ram of the press and movable toward and from the die. It has been found that under certain conditions of use, difficulty is experienced in disposing of the slugs or punchings removed from the work, this difficulty being particularly pronounced when the punching devices must be mounted very close together.

One of the objects of this invention is to provide a punching device which is so constructed that the punch is stationary and the die is movable toward and from the punch. Another object of this invention is to provide a punching device of this type in which the slugs or punchings are discharged from the die above the work which is being operated upon. Another object of this invention is to provide a punching device of improved and simplified construction, and in which the punch and die units are readily removable from the holder, and in which the die unit is mounted for reciprocation toward and from the punch.

It is also an object of this invention to provide a punching device of this type with a pilot pin of improved construction for cooperation with templates or other locating devices to facilitate the positioning of the punching devices relatively to each other on a press.

Another object of this invention is to provide an improved method of perforating work, in accordance with which the press may be operated on different kinds of work with comparatively little interruption. A further object is to provide an improved method of accurately positioning punching devices on a bolster plate.

Another object of this invention is to provide a punching device in which the punch and die units are mounted and guided in a holder in correct relation to each other in such manner that the forces exerted on the units by the ram are transmitted to the bed of the press without first acting on the holder.

Another object of this invention is to provide an adapter by means of which punching devices may be mounted on a press brake or elongated

base in such a manner as to be readily adjustable toward and from each other. Another object of this invention is to provide an adapter of this type in which the punching devices may be adjusted transversely of the bed of the press brake, as well as lengthwise thereof.

Other objects and advantages of this invention will appear from the following description and claims.

In the accompanying drawings:

Fig. 1 is an elevation, partly in section, of a punching device and an adapter embodying this invention and showing the punching device mounted for operation on a press brake.

Fig. 2 is a sectional plan view thereof, on line 2—2, Fig. 1.

Fig. 3 is a sectional elevation thereof, on a larger scale, on line 3—3, Fig. 1.

Fig. 4 is a fragmentary front elevation of an adapter for mounting a punching unit on the bed of a press brake and of a punching device mounted on the adapter.

Fig. 5 is a fragmentary elevation, partly in section, of a punching device mounted on a template.

Fig. 6 is a top plan view of a portion of a T-slotted bolster plate having a plurality of punching devices positioned thereon with the aid of a template.

Fig. 7 is a side elevation, partly in section, of my improved punching device mounted on a press brake by means of an adapter of modified construction.

Fig. 8 is a horizontal section taken along line 8—8, Fig. 7.

Fig. 9 is a fragmentary sectional elevation thereof, on line 9—9, Fig. 7.

Fig. 10 is a fragmentary sectional elevation on line 10—10, Fig. 8.

Fig. 11 is an elevation, partly in section, of one of the punching devices shown in Fig. 6.

My improved punching devices may be used in connection with a press or any other machine or apparatus having a stationary part or bed on which the punching devices may be positioned, and a ram or other part movable toward the stationary part for actuating the punching devices. The term "press" is herein used to designate any power actuated machine or apparatus for actuating the punching devices and the terms "bed" and "ram" are herein employed to designate respectively the stationary and movable parts of such machine or apparatus. In the accompanying drawings, 14 represents the bed of a press and 15 the ram, see Fig. 7, which may have

an extension 16 of any suitable form secured thereto. In Figs. 1 to 4 and 7 to 10, the bed and ram of a press brake are shown by way of example.

Each of my punching devices includes a holder 18 for the punch and die units, the holder shown in the drawings by way of example, including a base 19 and a head 20, the base and head being connected at the rear end of the holder and having other portions thereof spaced apart to form between them a gap into which the work 21 may be inserted. Holders of this type have heretofore been used in connection with punching devices and of themselves do not constitute this invention.

In punching devices of this type as heretofore made, the die unit was mounted in the base of the holder and the punch unit was slidably mounted in the head of the holder and was movable toward and from the die unit. In the construction shown in these drawings, this condition is reversed and the punch 22 is stationarily mounted in the base 19 of the holder, and a die unit is movably mounted in the head 20 of the holder. The die unit may be formed of a single piece die as has heretofore been customary, but preferably the die unit includes a die 24 removably held in the lower portion of a die carrier 25 which is mounted to move vertically in an accurately formed guideway, such, for example, as an aperture in an enlargement 26 of the head 20 of the holder, the die being positioned in the carrier so that when the carrier is moved downwardly from the positions shown in Figs. 1 and 3 to the position shown in Fig. 7, the punch 22 will be entered into the hole in the die, after passing through the work 21.

In order to remove the slugs or punchings from the die, I provide the die carrier 25 with an inclined passage or channel 27, the lower end of which terminates at the upper face of the die to receive the punchings from the hole in the die 24, and the upper end of which terminates at the upper portion of a side of the die carrier, so that slugs passing out of the hole in the die into the passage 27 will accumulate in the passage and will eventually be discharged from the upper end of this passage and drop upon the work 21, or if desired, the die carrier with the die may from time to time be lifted out of its hole in the head 20 of the holder so that the slugs or punchings may be dumped out of the passage 27.

The die 24 in the construction shown is held in its carrier by fitting snugly in the carrier and, consequently, may be driven out of its operative position in the die carrier and replaced by another die having a hole of different size.

The punch 22 is preferably provided with the usual punch head 28, to which the punch may be secured in any suitable manner, for example, as shown in Fig. 3, in which the punch has a portion of reduced diameter which extends into an aperture in the head 28. The punch, consequently, forms an annular shoulder 30, which rests on the upper surface of the punch head 28 and the punch may be permanently secured to the punch head in any suitable manner, for example, by swaging as indicated at 31.

In punching devices as heretofore constructed, a pilot pin was mounted on the holder to extend downwardly therefrom and in axial alignment with the punch die. If a downwardly extending pilot pin is desired on the punching devices herein shown, this can be done by providing the

punch with a portion 29 which extends through the hole in the head to the desired distance below the bottom face of the head, thus forming a pilot pin.

The punch unit preferably includes any suitable stripping means for withdrawing the punch from the work. In the construction shown, such stripping means include a stripper member 33, which is suitably mounted on a sleeve 34 extending about the punch 22. The lower end of this sleeve is preferably provided with an outwardly extending flange 35. This flange cooperates with a corresponding inwardly extending flange 36 formed on an upward cylindrical extension 37 of an abutment ring 38, and 39 represents a stripper spring which is interposed between the abutment ring 38 and the stripper 33. The punch 22 preferably terminates slightly below the upper face of the stripper 33.

It will be readily seen that when the ram 16 moves the punch carrier downwardly from the position shown in Fig. 1, to the lower position shown in Fig. 7, the die 24 will engage the upper face of the work and move the work downwardly so that the stripper 33 is depressed against the resistance of the spring 39 until the punch 22 has passed through the work and into the lower end of the die 24. Upon upward movement of the ram 16, the spring 39 forces the stripper upwardly into the positions shown in Figs. 1 and 3, thus stripping the work from the punch 22. The construction described also has the advantage that the sleeve 34 and stripper 33 serve to guide and support the punch in correct relation to the die 24.

The die carrier may be mounted for correct movement toward and from the punch in any suitable manner, for example, by accurately aligned holes or apertures of any desired sizes or shapes. In order to facilitate the manufacture of my improved punching devices, I preferably make the die carrier, the stripper, the punch head, and the abutment ring of the same diameter, and consequently, a pair of aligned holes 40 and 41 may be accurately bored through the enlarged portions of the head and base of the holder completely from the top of the head through the bottom of the base, these holes being spaced apart by the gap between the head 50 and base of the holder. Consequently, the punch head which is in the lower part of the hole in the base of the holder will rest upon any support upon which the holder 18 is mounted. Consequently, when the holder is detached from its support, a punch of the desired size and its stripper assembly may be inserted upwardly through the bottom of the hole 41 or downwardly through the upper hole 40 into the lower hole 41. A punch holder of this construction carries none of the strains resulting from the punching operation, so that the holder merely serves to guide the die in its movement toward and from the punch.

Suitable means are preferably provided for yieldingly holding the movable die carrier and the die in an elevated position slightly above the punch, so as to facilitate the insertion of work between the punch and die. In the construction shown, by way of example, a leaf spring 44 is provided for this purpose, which is suitably secured to the die carrier and the free end of which may engage the upper face of the head 20 of the holder. This leaf spring may be held in the die carrier in any suitable or desired manner. For example, the die carrier may be pro-

vided in the upper portion thereof with a transversely extending hole 45 which may terminate in the slug passage 27, as shown in Figs. 1 and 7. The spring 44 may be provided with a pair of substantially cylindrical bent portions or wings 46 formed to fit snugly within the hole 45. Any other means for yieldingly supporting the die carrier above the punch may be provided.

It may be desirable at times to employ a pilot pin in the upper portion of the punching device, coaxial with the punch and die, for correctly positioning the punching device on the bed of a press. In the construction shown, a pilot pin 48 is provided in the upper portion of the die carrier in axial alinement with the center of the hole in the die and with the punch 22. The lower end of this pilot pin 48 may extend into the transverse hole 45 of the die carrier, and the upper end of the pilot pin extends above the top surface of the die to an extent sufficient to co-operate with a template. Since, however, the upper end of the die carrier is engaged by the movable ram for actuating the punching device, the pilot pin 48 is slidably mounted in a hole in the upper portion of the die carrier, so that when the ram descends, the pilot pin 48 may be pushed down into the carrier. A spring is preferably employed for yieldingly urging the pilot pin 48 into its upper position. In the construction shown for this purpose, the spring member 44 may be provided with an arm or leaf 49 which extends underneath the pilot pin in a position to yieldingly urge the pilot into its upper position. The pilot pin 48 is preferably provided at its lower end with a burr or enlargement 50 which prevents the pilot pin from passing upwardly out of the vertical hole in which the pilot pin is located. Any other suitable means for urging the pilot pin into its upper position may be provided.

Any suitable gage may be employed for limiting the extent to which the work 21 is inserted into the gap in the holder, and in the construction illustrated by way of example, an adjustable gage bar 52 extends through a hole in the holder 18 and may be locked in position by means of a set screw 53 extending through a lug or projecting portion 54 of the holder. The gage is provided with a work engaging face, such as the face on the work engaging end of the gage bar 52, which extends parallel to the direction of movement of the work by the die relatively to the punch. Consequently, the movement of the work by the die will not cause any displacement of the work due to contact with the gage.

My improved punching devices may be mounted on presses in any suitable or desired manner. Preferably I provide in the base of the holder an upwardly extending threaded hole or aperture 56, in which a screw may engage for securing the punching device to a support. In Fig. 5, I have illustrated my improved punching device as mounted on a template 58 which may have a plurality of holes 59 accurately formed therein to receive the pilot pins 29 of a number of punching devices, one such punching device being shown in Fig. 5. The template 58 is also provided with a countersunk hole for each pilot pin hole 59, adapted to receive screws 60 for securing the punching devices to the template. Since the use of templates in connection with punching devices is well known, no means are shown for securing the template 58 to a bed 61 of a press, since any suitable means may be employed for this purpose.

In Figs. 6 and 11, I have shown a modified type of holder for use in connection with my punching devices and for use in mounting the punching devices on bolster plates of any suitable construction adapted to receive clamping means, such as bolts for securing punching devices thereto. These bolster plates may, for example, be in the form of T-slotted plates of the type commonly employed in connection with presses. The holders 63 shown in Figs. 6 and 11 are provided with longitudinal slots 64 and 65 in the heads and bases of the holders. The portions of the holders in which the punch and die units are arranged may be the same as those described in connection with Figs. 1 to 4. One or more bolts 66 may be inserted through the lower slot 65 of the holder into engagement with threaded nuts 67 arranged in the slots 68 of the bolster plate 69. The heads of the bolts 66 are preferably of the type having hexagonal holes or recesses in the upper portion thereof, which may be engaged by means of the lower end of a hexagonal bar 69a which may be extended through the upper slot 64 in order to operate on the bolts 66. Any other means for securing the punching devices to the bolster plate may be provided.

In order to correctly position the punching devices on a bolster plate, a template 70 is preferably provided for cooperation with the pilot pins 48 of the die carriers. The template 70 is provided with any desired number of holes 71 accurately formed in the template in accordance with the holes desired in the work. The various punching devices as shown in Fig. 6 are positioned under the template 70 so that their pilot pins 48 extend through the holes 71. This can best be accomplished by first supporting the template on three or more punching devices, and then shifting these punching devices and any others that are to be used horizontally on the bolster plate until the pilot pins snap into place through the holes in the template, which indicates that such punching devices are in the correct positions. The holders 63 of the punching devices are then secured to the bolster plate in such positions by tightening the bolts 66, and the template may be removed when all of the punching devices are secured on the bolster plate.

The construction disclosed in Figs. 6 and 11 may be used in carrying out my improved method of perforating work. In accordance with this method, a number of bolster plates are provided for each press and the punching devices for any job may be set up on a bolster plate before the plate is placed on the bed of a press. This can be readily done by using templates 70 as illustrated in Figs. 6 and 11. After the punching devices have been accurately positioned on a bolster plate and secured thereto, the bolster plate is ready to be placed on the bed of a press and while this bolster plate is in use, the punching devices for another job may then be set up on another bolster plate which can be placed on the bed of the press immediately after the desired number of pieces have been punched by means of the devices on the first bolster plate. If desired, several plates may have the punching devices set up thereon, ready to be placed in the press. By means of this method, the press may be kept in almost continuous use, since as soon as the press has completed a job by perforating the required number of pieces of work, the T-slotted plate for that job is slid out of the press and another T-slotted plate having another series of punching devices set up for another job.

is put in the press. The punching devices are then removed from the bolster plate which has been taken from the press and are ready for use wherever desired.

In case of jobs requiring bolster plates which are too large to be readily removed from the press, the punching devices can be set up on the plate while the same is securely bolted to the press bed.

It is frequently desirable to mount punching devices on press brakes, and I have, consequently, shown in Figs. 1 to 4 and 7 to 10, two forms of adapters by means of which punching devices as herein shown as well as punching devices of other types may readily be adjustably mounted on press brakes. In Figs. 1 to 4, I have shown adapters which are intended for use where all of the holes to be punched in the work are arranged in a straight line and where the adapters are adjustable only lengthwise of the bed of press brake; and in Figs. 7 to 10, I have shown adapters usable in case the holes are not all in a straight line, and in which the adapters are adjustable both lengthwise and transversely of the bed. In both of these constructions, I secure on the bed of the press brake a rail of any suitable form on which the adapters can be mounted. This rail 73 as shown by way of example in the drawings is in the form of a bar of dovetail cross section, having the longitudinal edges thereof flaring upwardly and outwardly and having a substantially flat upper surface. This rail may be secured to the bed of a press in any suitable manner (not shown) and is preferably provided with a downwardly extending rib 14 secured to the underface thereof and extending into the space between the two parts of the base 14.

In the construction shown in Figs. 1 to 4, the adapter includes a clamping member 76, which is formed to be secured to the bed rail 73. In the particular construction shown for this purpose, the clamping member is provided at the rear end thereof with a downwardly extending flange 77 having an inclined face 78 adapted to engage the rear inclined edge of the dove-tailed rail 73. The front end of the adapter is also provided with a downwardly extending flange 79 having an inner face against which a wedge member 80 may engage. This wedge member has an inclined face 81 adapted to engage the inclined front face of the rail 73, and any suitable means may be employed for forcing this wedge member upwardly into gripping engagement with the bed rail. For example, a screw 82 may be employed extending loosely through a hole in the wedge member and engaging a threaded hole in the clamping member 76. Consequently, by tightening the screw 82, the wedge member will secure the clamping member securely into clamping engagement with the bed rail 73.

The punching device may be secured to the adapter in any suitable or desired manner. For example, the adapter may be provided with an accurately located hole 83 to receive the pilot pin of a punching device, for example, the pilot pin or extension 29 of the punch shown in the drawings. The adapter may also be provided with a suitable shouldered aperture 84 adapted to receive a part of a screw 85 which may enter into the threaded hole 56 of the holder of the punching device. These adapters may be secured in any desired position lengthwise of the bed rail so that the holes to be punched in the work may be located at the desired distances from each

other. Any other means for securing the punching devices to the adapter may be provided, if desired.

In Figs. 7 to 10, I have illustrated adapters capable of two adjustments relatively to the rail 73. In this construction, a clamping member 87 is provided which may be secured to the bed rail in the same manner as the one shown in Figs. 1 to 4. The upper face of this clamping member 10 is provided with a groove or channel extending transversely of the bed rail, the channel being formed between two upwardly extending flanges 88. A slide member 89 is arranged in this channel for adjustment on the adapter in the direction of its length, or in other words, crosswise of the length of the bed rail 73, the slide 89 being of a thickness equal to the height of the flanges 88 and being provided with a slot 90 through which a clamping or set screw 91 extends, the set screw engaging in a threaded hole 92 in the front portion of the clamping member 87. If a greater range of adjustments is desired, another threaded hole 94 may be provided in the adapter 87, and the clamping screw 91 can be removed from the position in which it is shown in Figs. 7, 8 and 10, whereupon the slide 89 may be moved back until the slot 90 is in registration with the hole 94, and the screw 91 can then be inserted through the slot 90 and into the hole 94.

The slide 89 of the adapter is provided with any suitable means for mounting the holder 18 of the punching device thereon. For example, the slide member may be provided with a hole adapted to receive the pilot pin 29 of the punching device and may also be provided with an aperture to receive the head of a screw 93 for engaging in the threaded hole 56 of the holder for securing the punching device to the slide 89.

In the use of this adapter, the clamping member 87 may be secured in any desired position lengthwise of the bed rail 73 by means of the wedge member 80. For positioning the punching device crosswise of the rail, the set screw 91 may be released and the slide 89 moved between the flanges 88 to position the punching device crosswise of the rail 73 and when the punching device is in the desired position, the set screw 91 is tightened for locking the punching device in such position.

Punching devices of the type described in which the die is movable toward and from the punch have a number of advantages over punching devices as heretofore used. In the first place, no holes are required in a bolster plate or in the lower portion of the holder 18 through which the slugs or punchings may be discharged. Consequently, the punching devices may be arranged as closely together as desired, since sufficient clearness to permit punchings to be discharged need not be provided. By means of the constructions shown the die carrier discharges the slugs or punchings from a side thereof, for example, from the front as shown in the drawings, and these punchings may, consequently, be dropped on the work 21 and will, consequently, be discharged from the press when the work is withdrawn. The construction shown also has the further advantage that the force exerted by the die and against the punch to force the punch through the work is not exerted against the holder 18 or the base 19 thereof but directly to the bed 14 of the press through the parts on which the holder is mounted, which in the construction shown in Figs. 1 to 4 and 7 to 10 is the adapter 75 and the rail 73. In the construction shown in

Fig. 5, the punch head 28 rests on the template 58, and consequently, the punching pressure is transmitted by the head of the punch directly to the template 58 and from the template to the bed 61 of the press or other parts on which the template is mounted. In Fig. 6, the punching pressure is transmitted by the punch head directly to the T-slotted bolster plate 69.

The construction described also has the advantage that the punch and die units can be easily removed from their holders, since they merely float in the guide holes in the holders in which they are arranged. Consequently, the die carrier can be easily removed for sharpening the die or for insertion of another die and similarly the punch can be easily removed from its hole in the base of the holder and out of the guide sleeve 34 thereof. The stripper unit including the abutment ring 37, stripper 33 and guide sleeve 34 form a unit which may be replaced by units having guide tubes 34 of different diameters to cooperate with punches of different diameters.

I have herein described my improved punching device as constructed with the punch and die in vertical alinement, but it will be obvious that the invention herein described can be equally well employed with a holder in which the axis of the punch and die is at an angle to the vertical. Consequently, the word "base" is herein used to describe that part of the holder which supports the stationary punch in its operative position, and the word "head" is employed to designate the part of the holder which guides the movable die, regardless of whether the "head" is above the "base" or in any other position relatively thereto.

I claim as my invention:

1. A punching device for use on a press having a stationary bed and a ram movable toward and from said bed, said punching device including a holder having a unitary head and base spaced apart to receive between them the work, axially aligned apertures extending through said head and base, a punch and stripper unit arranged in the aperture in said base, and a die unit movably mounted in the aperture of said head and extending above said head for engagement by the ram of the press.

2. A punching device for use on a press having a stationary bed and a ram movable toward and from said bed, said punching device including a holder having a head and a base spaced apart to receive between them the work, axially aligned apertures extending through said head and base, a punch and stripper unit arranged in the aperture in said base, and a die unit movably mounted in the aperture of said head and extending above said head for engagement by the ram of the press, said punch and stripper unit being movable through the bottom of said aperture in said base, whereby pressure exerted by said ram on said punch and stripper unit is transmitted to the bed of the press without passing through said holder.

3. A punching device for use on a press having a stationary bed and a ram movable toward and from said bed, said punching device including a holder having a unitary head and base spaced apart to receive between them the work, axially aligned apertures of equal diameters extending through said head and base, a punch and stripper unit arranged in said aperture in said base, a die carrier movably mounted in the aperture in said head, and a die mounted on said carrier in position to cooperate with said punch.

4. A punching device for use on a press having a stationary bed and a ram movable toward and from said bed, said punching device including a holder having a head and a base spaced apart to receive between them the work, axially aligned apertures in said head and said base, the aperture in said base extending through the same, a punch unit and a die unit, one of said units being arranged in said aperture in said base and being movable through the bottom of said aperture when said holder is removed from the press and being supported by said bed when the holder is mounted on a press, whereby pressures transmitted to said unit from the ram are transmitted to said bed without passing through said holder.

5. A punching device for use on a press having a stationary bed and a ram movable toward and from said bed, said punching device including a holder having a head and a base spaced apart to receive between them the work, axially aligned guideways on said head and base, a punch and stripper unit arranged in and free to move lengthwise on one of said guideways, a die unit on the other guideway and free to move lengthwise thereof, the unit on the guideway in said base being supported by the bed of the press, independently of said holder to transmit pressures received from said other unit to the bed of the press without first transmitting such pressures through said holder.

6. A punching device for use on a press having a stationary bed and a ram movable toward and from said bed, said punching device including a holder having a head and a base spaced apart to receive between them the work, axially aligned apertures extending through said head and base, a punch and stripper unit arranged in said aperture in said base, said punch having a head of a diameter to slide lengthwise in said aperture in said base and through the bottom of said aperture, a die unit in the aperture in said head and movable toward and from said punch and arranged to be actuated by the ram, said punch transmitting pressures received from said die unit to the bed of the press without transmitting such pressures to said holder.

7. A punching device for use on a press having a stationary bed and a ram movable toward and from said bed, said punching device including a holder having a unitary head and base spaced apart to receive between them the work, axially aligned apertures in said head and base, a punch arranged in said aperture in said base, a die holder in said aperture in said head and extending above said head in position to be engaged by said ram, and a die mounted on said die holder in operative relation to said punch and having a hole extending therethrough, said die holder having a passage extending from said hole in said die to the portion of said die holder which extends above said head, to discharge punchings.

8. A punching device for use on a press and including a holder having a unitary base and head spaced apart to receive between them the work, a punch mounted on said base, a die mounted on said head and movable axially toward and from said punch to engage the work and move the same relatively to said punch to force the work around the punch, and means for yieldingly supporting said die in spaced relation to said punch to facilitate insertion of the work between said punch and die.

9. A punching device for use on a press having

a stationary bed and a ram movable toward and from said bed, said punching device including a holder having a head and a base spaced apart to receive between them the work, axially aligned apertures in said head and base, a punch and stripper unit arranged in the aperture in said base, a die carrier movably mounted in the aperture of said head, and a die on said carrier in position to cooperate with said punch.

10. A punching device for use on a press having a stationary bed and a ram movable toward and from said bed, said punching device including a holder having a head and a base spaced apart to receive between them the work, means on said base for receiving a punch, and a die unit slidably supported on said head for movement into and out of operative relation to said punch, said die unit having a portion extending above said head of said holder for engagement with the ram of a press.

11. A punching device for use on a press having a stationary bed and a ram movable toward and from said bed, said punching device including a holder having a head and a base spaced apart to receive between them the work, means on said base for receiving a punch, a die unit slidably supported on said head for movement into and out of operative relation to said punch, said die unit having a portion extending above said head of said holder for engagement with the ram of a press, and a spring engaging said die unit for yieldingly urging the same into a position in spaced relation to said punch to facilitate the insertion of work between said punch and die unit.

12. A punching device for use on a press having a stationary bed and a ram movable toward and from said bed, said punching device including a holder having a head and a base spaced apart to receive between them the work, means on said base for supporting a punch, a die unit slidably supported on said head for movement into and out of operative relation to said punch, said die unit having a portion extending above said head of said holder for engagement with the ram of a press, and a pilot pin extending upwardly from said die unit in coaxial relation therewith and yieldingly mounted to permit said pilot pin to recede into said die unit when engaged by the ram of the press.

13. A punching device for use on a press having a stationary bed and a ram movable toward and from said bed, said punching device including a holder having a head and a base spaced apart to receive between them the work, axially aligned apertures in said head and base, a punch arranged in said aperture in said base, a die holder in said aperture in said head, and extending above said head in position to be engaged by said ram, a die mounted on said die holder in operative relation to said punch, a pilot pin arranged in an aperture in the upper end of said die, coaxial with said die and punch, and a spring for urging said pilot pin into its upper position and permitting said ram to press said pilot pin into said aperture.

14. A punching device for use on a press including a holder having a head and a base spaced apart to receive between them the work, said base having a portion thereof formed to receive a punch having a head secured thereto, a portion of said punch extending through said head and below said base to form a pilot pin, and a die mounted in said head to move toward and from said punch.

15. Apparatus for mounting a plurality of punching devices on the bed of a press brake, including a rail formed for securing on said bed and having a substantially flat upper face and upwardly and outwardly inclined longitudinal edge portions, a clamping member for each punching device and for mounting upon said rail and having a portion extending crosswise of said rail and downwardly extending flanges, one of said flanges engaging one inclined edge portion of said rail, a wedge member arranged between said other flange and the other edge portion of said rail, means for moving said wedge member into clamping engagement with said last mentioned flange and edge portion to lock said clamping member on said rail, and means for securing a punching device on said clamping member, said clamping members being adjustable lengthwise of said rail when said wedge member is released 20 from clamping engagement with said rail.

16. Apparatus for adjustably mounting a plurality of self-contained punching devices on a bed of a press brake, including a rail of substantially uniform cross sectional shape throughout its length and constructed to be secured to said bed, a plurality of adapters on said rail and movable lengthwise thereof to different positions along said rail, means for clamping said adapters in the desired positions lengthwise of said rail, 30 and means for securing a punching device to each adapter, whereby a plurality of holes may be punched simultaneously in work in the desired spaced relation to each other.

17. Apparatus for adjustably mounting a plurality of self-contained punching devices on a bed of a press brake, including a rail of substantially uniform cross sectional shape throughout its length and constructed to be secured to said bed, a plurality of adapters on said rail and movable lengthwise thereof to different positions along said rail, means for clamping said adapters in the desired positions lengthwise of said rail, slides on said adapters adjustable in a direction transversely of said rail, means for locking said 45 slides against movement relatively to said adapters, and means for securing a punching device to each slide, whereby said punching devices may be adjusted both lengthwise and transversely of said rail.

18. An adapter for adjustably mounting a self-contained punching device on a rail, including a clamping device having means for securing said clamping device in the desired position lengthwise of said rail, a slide mounted on said clamping device for movement transversely of said rail, means for securing said slide in the desired position on said clamping device, and means for securing a punching device to said slide.

19. A method of perforating work by means of a plurality of unitary punching devices, each of which includes a die and a punch cooperating with the die, said method comprising mounting a plurality of said punching devices on a single bolster plate, formed for universal adjustment and mounting of said punching devices thereon, in correct relation to each other to produce the work desired, placing said plate with said punching devices secured thereto on the bed of a press in operative relation to the ram thereof, perforating the required number of pieces of work, then removing said bolster plate from the press, and removing the punching devices therefrom for use on other work.

20. A method of perforating work on a press having a ram and a bed on which bolster plates,

formed for universal adjustment and mounting of said punching devices thereon, may be removably mounted, which includes positioning a plurality of self-contained punching devices each including a die and a punch cooperating with the die, in correct relation to each other to punch holes in the work in the required relation to each other and to the work, perforating the desired number of pieces of work while the bolster plate is in operative relation to the press, and securing another set of punching devices on another bolster plate for operating on other work, removing said first mentioned bolster plate from the press when the desired number of pieces have been perforated and immediately positioning said second bolster plate on said press for operating on other work, whereby the idle periods of the press between different jobs are shortened.

21. A method of perforating sheets of material in a press having a ram and a bed on which bolster plates, formed for universal adjustment and mounting of said punching devices thereon, may be removably positioned, which includes setting upon a plurality of said bolster plates, punching devices each including a die and a punch cooperating with the die, in correct relation to each other, each bolster plate having its punching devices arranged for a different job, successively positioning said bolster plates with their punching devices on the press, and perforating the desired number of pieces of work with each bolster plate, whereby the time required to set the punching devices on the bolster plates involves no delay in the operation of said press.

22. A method of mounting on a bolster plate, by means of an apertured template, punching devices each including a punch and a die in operative relation to each other and a pilot pin coaxial with the punch and die and yieldingly urged into a position above the punching device, said method including placing said template upon a plurality of said punching devices resting on

the bolster plate, moving said punching devices along the surface of the bolster plate until their pilot pins enter the apertures of the template, and then securing said punching devices to said bolster plate.

- 5 23. A method of mounting on a bolster plate, by means of an apertured template, a punching device including a punch and a die in operative relation to each other and a pilot pin coaxial with the punch and die and yieldingly urged into a position above the punching device, which includes placing said punching device on a bolster plate below said template with said template depressing said pilot pin, shifting said punching device laterally on the surface of said bolster plate until said pilot pin enters the desired aperture in said template, and then securing said punching device on said bolster plate while said pilot pin is in said aperture.
- 10 24. A sheet material punching apparatus for use between the bed and ram of a press, comprising a plurality of punching devices, each of which includes a stationary punch and a die movable toward and from the punch, said die extending into a position to be actuated by the ram of the press for perforating the work, a pilot pin arranged axially on said die, spring means for urging said pin into an operative position in which said pin projects above the die, said pin being movable against said spring means into a position in which said pilot pin does not project above said die, a template for cooperation with a plurality of said punching devices, and having accurately located holes into which said pilot pins are forced by said spring means when said punching devices are in correct relation to said template, and means for securing said punching devices in correct relation to each other when their pilot pins are in the holes of the template, said pilot pins receding into said die when engaged by said ram.
